APPARATUS FOR MIXING MATERIALS WITH A FLOWING LIQUID

Gwilym Mansell de May, London, England, assignor to
Smith Hayden & Company Limited, Molesey, England,
a company of Great Britain

Filed May 26, 1967, Ser. No. 7,271

Claims priority, application Great Britain Dec. 16, 1966

Term of patent 3½ years

(Cl. D23—3)

FIG. 1.

FIG. 2.

FIGURE 1 is a front view of apparatus embodying my design;

FIGURE 2 is an inverted plan view thereof;

FIGURE 3 is a side-elevational view thereof as seen from the left of FIGURE 1; and

FIGURE 4 is a top plan view as seen from the top of FIGURE 1.

I claim:

The ornamental design for an apparatus for mixing materials with a flowing liquid, substantially as shown.
